UNITED STATES PATENT OFFICE.

HARRY GUILBERT, OF PROVO, UTAH.

PHONOGRAPH.

1,342,284.

Specification of Letters Patent. Patented June 1, 1920.

Application filed October 25, 1919. Serial No. 333,170.

To all whom it may concern:

Be it known that I, HARRY GUILBERT, a citizen of the United States, and a resident of Provo, in the county of Utah and State 5 of Utah, have invented a new and Improved Phonograph, of which the following is a full, clear, and exact description.

This invention relates to improvements in phonographs, an object of the invention being to provide improved sound amplifying means which practically eliminates the metallic sounds of the needle on the record and reproduces the finest of tones and sounds.

A further object is to provide a phonograph having a sounding board and an improved mounting for the tone arm which is located under the sounding board and connected to the central portion of the sounding board and which support also carries a horn 20 or horns to amplify the sound.

A further object is to provide a phonograph of simple, inexpensive construction which can be utilized in connection with any ordinary box or casing open at the bottom 25 and which will give improved results.

With these and other objects in view the invention consists in certain novel features of construction, and combinations and arrangements of parts, as will be more fully 30 hereinafter described and pointed out in the claims.

In the accompanying drawings—

Figure 1 is a view in side elevation illustrating my improvements;

Fig. 2 is a top plan view;

Fig. 3 is a view in longitudinal section on the line 3—3 of Fig. 2;

Fig. 4 is a view in transverse section on the line 4—4 of Fig. 1;

Fig. 5 is a perspective view of my improved bridge; and

Fig. 6 is a view showing a modification.

1 represents an open skeleton frame which may be made of wood or any other suitable 45 material and which is preferably rectangular in form as indicated, although, of course, I do not wish to be limited to any particular shape of this frame.

A sounding board 2 is secured on top of 50 the frame 1 preferably by means of glue or some other adhesive so as to properly hold the sounding board.

A bridge 3 is secured to blocks or cleats 4', the latter secured to the under face of 55 the sounding board 2 at or near its center.

This bridge 3, shown in perspective in Fig.

5, is preferably made up of relatively thin sections of veneer glued together and is of angular shape so that one end 4 provides a ready surface for attachment to the cleats 4' 60 while the other and longer end projects under the sounding board and terminates in proximity to one corner of the sounding board and under an opening 5 in the sounding board.

A block 6 of the same shape as the opening 5, but slightly smaller than the opening, is secured upon the bridge 3 and supports a tone arm 7. It is, of course, to be understood that the block 6 and the bridge 3 have 70 openings 8 and 9 respectively therein registering with the interior of the tone arm to allow a free passage of the sound waves.

A throat chamber 10 is secured to the end of the bridge 3 and into this throat chamber the sound waves freely pass. A laterally projecting horn 11 communicates at its upper inner end with the chamber 10 and a longitudinally projecting horn 12 communicates at its end with the side of 80 the chamber 10. The horns 11 and 12 have outlets 13 and 14 respectively in their lower portions to direct the sound downwardly, and it is, of course, apparent that during the shipment of the device, it will be ad- 85 visable to provide some form of support for the free ends of the horns, yet in ordinary use no support is needed other than their attachment to the throat chamber 10.

The tone arm 7 carries the ordinary sound 90 box 15 with its needle 16 adapted to engage a record disk 18 on a turntable 19 mounted on a platform 20 on the sounding board 2 and I may employ any desired form of motor, not shown, for turning the turntable. 95

A muffler 21 is mounted to slide through a slot 22' in the throat chamber 10 and is operated by means of a lever 22 projecting through a slot 23 in the sounding board 2. A convenient means of connecting the lever 100 with the muffler is to provide a crank shaft 24 having rotary mounting at the under side of the sounding board and connect one crank 26 of the crank shaft 24 with the lever 22 and connect the other crank 27 of the 105 shaft 24 with the muffler 21 by means of a link 25. The bridge 3 is made with a longitudinal slot 28 to accommodate this crank arm 27 as the muffler 21 is supported just below the bridge.

It will therefore be noted that the tone arm and all of the sound amplifying struc-

ture is supported at the free end of the bridge 3 and the latter is supported at substantially the center of the sounding board 2. Such a structure allows a more or less yielding mounting to the sound amplifying means and prevents metallic sounds, such as are common with rigidly mounted tone arms. Furthermore, the sounding board 2 operates to amplify the sounds which are 10 thrown downwardly and hence a better result is had by reason of the construction and mounting of the parts, such as above explained, than is possible with the ordinary type of phonograph in general use.

15 With my improved structure, as above explained, any form of casing or box with an open bottom can be utilized and I have not attempted to illustrate any particular form of casing as this is well within the cabinet 20 maker's art. My invention resides in the utilization of the sounding board and the particular mounting and arrangement of sound amplifying means.

25 Various slight changes may be made in the general form and arrangement of parts described without departing from the invention, and hence I do not limit myself to the precise details set forth but consider myself at liberty to make such changes and 30 alterations as fairly fall within the spirit and scope of the appended claims.

In the modification shown in Fig. 6, a tone modifying gate A is shown located directly under the tone arm, and pressed 35 into engagement by means of a spring B. This gate A will vary the tone to suit the taste of the operator.

I claim:

1. A phonograph, comprising means for 40 supporting a record, a bridge, and a tone arm supported by the free end of the bridge.

2. A phonograph, comprising means for

supporting a record, a sounding board having an opening therein, a bridge connected at one end to the sounding board and at its 45 free end spaced from the sounding board, and a tone arm supported on the bridge and projecting through said opening.

3. A phonograph, comprising a sounding board, a bridge secured at one end to the 50 central portion of the sounding board and at its free end spaced from the sounding board, a block secured on the free end of the bridge, a tone arm mounted on the block, said sounding board having an opening 55 therein accommodating the tone arm and the block, said block and bridge having openings therein registering with the tone arm, and sound amplifying means connected to the bridge.

4. A phonograph, comprising a frame, a horizontal sounding board secured on the frame, means on the sounding board supporting a record, an angular bridge, means securing one end of the bridge to the central 65 portion of the sounding board below the same with said bridge spaced from the sounding board, tone arm supporting means on the free end of the bridge projecting through the sounding board, and sound amplifying means carried by the bridge.

5. A phonograph, comprising an open frame, a horizontal sounding board secured on the frame and having an opening therein, a bridge secured to the sounding board 75 but spaced therefrom and projecting horizontally under the sounding board, a tone arm support on the bridge, said sounding board having an opening receiving said tone arm support, a tone arm on said support, 80 and sound amplifying means suspended from the free end of the bridge.

HARRY GUILBERT.
